UNITED STATES PATENT OFFICE.

HJALMER C. GUSTAFSON AND SVEN GUSTAFSON, OF DENVER, COLORADO.

AUTOMATIC VALVE.

1,248,650.

Specification of Letters Patent.

Patented Dec. 4, 1917.

Application filed February 5, 1917. Serial No. 146,589.

To all whom it may concern:

Be it known that we, HJALMER C. GUSTAFSON and SVEN GUSTAFSON, citizens of the United States, residing at Denver, in the county of Denver and State of Colorado, have invented new and useful Improvements in Automatic Valves, of which the following is a specification.

The present invention is directed to improvements in automatic valves, and more particularly to that type designed for use in flushing tanks for water closets.

The invention has for its object to provide a device of this character constructed in such a manner that the same will operate to cut-off the supply to the tank without the objectionable "hissing" now prevalent in devices of this kind.

A further object of the invention is to provide a valve of this type which is exceedingly simple in construction and noiseless in operation.

A still further object of the invention is to provide a device of this character which consists of a minimum number of compactly related parts which can be conveniently assembled or disassembled.

Still another object of the invention is to provide a valve of this nature which is durable, and can be manufactured at a minimum cost.

With these and other objects of similar nature in view, the invention consists in the construction, combination and arrangement of parts set forth in and falling within the scope of the appended claims.

In the drawings:—

Figure 1 is a side elevation of the device, partly in section, and showing the same mounted within the conventional form of flush tank.

Fig. 2 is an enlarged vertical central sectional view through the device, showing the same in its open position.

Fig. 3 is a fragmentary central sectional view through a slightly modified form of the invention, the same being shown in full lines in its closed position.

Fig. 4 is a detail view of the valve stem. Referring to the drawing, 1 designates a casing consisting of upper and lower sections 2 and 3, respectively. The section 3 has its upper end formed with a comparatively shallow circular seat 4 which receives the lower end of the section 2, whereby the

sections may be readily engaged or disengaged, and held in clamped engagement by the bolts 5.

Depending from the top 6 of the section 2 is a tubular guide 7, and since said guide depends into the section, an annular pressure chamber 8 is produced, the purpose of which will appear later. A bridge-piece 9 is provided and extends from the guide 7 to the wall of the section 2, said bridge-piece having port 10 formed longitudinally therein, the inner end of which is in communication with the bore 11 of the guide, while the outer end thereof opens through the wall of the section 2.

Suitably secured in the outer end of the port 10 is the inner end of the curved pipe 12, which terminates in a vertical section 13, which empties into the tank 12'.

Spaced ears 14 are formed upon the top of the section 2, and pivotally connected between said ears is one end of the float arm 15. Movable in the bore 11 of the guide 7 is a stem 16, the upper end of which has threaded thereon a head 17, said head having a slot 18 for engagement with the float arm 15. Thus it will be seen that as the float arm rises and falls that the stem will be moved vertically in the bore 11 in an obvious and well known manner.

Also mounted on the top 6 is a lug 19 having a socket 20 formed therein for receiving the coil spring 21, which encircles the stem 22 of the valve 23, said stem having a head 24 on its upper end adapted to bear upon the upper end of the spring 21, while the lower end of said spring rests upon the bottom of the socket 20. The spring 21 is of such size that the head 24 is normally extended from the socket 20 so as to be engaged by the arm 15 as said arm swings downwardly during the flushing of the tank 12'. It is of course obvious that the head 24 will continue to move downwardly until the arm 15 engages the top of the lug 19, and at which time the spring 21 will be compressed, the purpose of which will appear later.

Formed interiorly of the top 6 is a seat 25, said seat having opening thereinto a passage 26, which affords communication between the chamber 8 and socket 20, and also accommodates the stem 22. The spring 21 normally tends to hold the valve 23 engaged with the seat 25. Formed in the wall of

the lug 19 is a port 27 through which air from the outside is admitted to the chamber 8 when the valve 23 is unseated.

The seat 4 is formed with a recess 28, 5 said recess having its base 29 formed with a plurality of ports 30 which open into the annular chamber 31 formed in the section 3. It will be noted that in the preferred form of the invention that the inlet pipe 32 extends through the chamber 31 and has its upper end extended above the plane of the base 29, thus constituting a seat 32' for co-operation with the valve disk 33, which is preferably formed from rubber, and has its 15 edge clamped between the sections 2 and 3, as clearly shown in Fig. 2 of the drawing.

Secured centrally of the disk 33 is a plug 34, said plug having a fluid passage 35 formed therein to permit water from the 20 pipe 32 to pass into the chamber 8. Depending from the section 3 is a tank filling pipe 36, which communicates with the chamber 31, and empties into the tank 12'.

Leading from the chamber 31 is a pipe 25 37, which has its upper end curved so as to discharge into the upper end of the usual overflow pipe 38.

The tank 12' is equipped with the usual form of plug valve 39, which is operated in 30 any well known manner when it is desired to flush the closet bowl.

The lower end of the guide 7 is spaced from the seat 4, and is counterbored to form a casing 40, the upper end of which is provided with a seat 41. The stem 16 is provided with a reduced extension 42 upon which is mounted a flexible valve 43, said valve being retained on the extension by the cap 44, said cap having an annular seat 45 40 carried thereby for engagement with the disk valve 33 when the same is in its open position, as clearly shown in Fig. 2 of the drawing. By providing the reduced extension 42 water is permitted to pass into the 45 port 10, and from thence to the pipe 13. The casing 40 is provided with vertically spaced ports 46 and 47, one of which is always closed by the valve 43.

In the modified form of the invention, as 50 shown in Fig. 3, the valve disk 33 is loosely mounted on the seat and is capable of limited vertical movement due to the fact that its edge is free. To hold the disk 33 in proper shape and in a rigid condition a 55 metal washer 48 is placed thereon. It will be noted in this instance that the edge of the disk 33 is so associated with the wall of the seat 4 and lower edge of the section 2 that water will be prevented from passing around the edge of said disk. The 60 operation and function of the disk 33 in this form is otherwise the same as in the preferred form of the invention.

As shown in Fig. 2, the flushing action is 65 in progress, and the float arm 15 falls in

the usual manner, and engages the head 24 carried by the stem 22, thereby disengaging the valve 23 from the seat 25, thus permitting the air to enter the chamber 8 through the passage 27. The valve 43 is then moved 70 downwardly under the action of the float arm 15 and disengages the seat 41 formed in the casing 40 before the valve 23 is unseated, thus releasing the pressure in the chamber 8 and permitting the valve disk 33 to 75 flex upwardly and engage the seat 45. It will be of course understood that the disk 33 engages the seat 43' formed by the lower end of the casing 40 only after the seat 45 has been drawn into the casing 40 by the 80 upward movement of the stem 16. Valve 43 also closes the port 47, thus completely cutting off the chamber 8 from a new supply of water from the inlet pipe 32. Water from the chamber now flows through the 85 port 46 and is discharged through the pipe 13 in an obvious manner. The water from the pipe 32 now flows under the disk 33, through ports 30 into the chamber 31, and from thence out of the discharge pipe 36 90 into the tank 12'.

It will be noted that an appreciable amount of water also flows upwardly in the refill pipe 37. By means of the air valve 23 air is admitted to the chamber 8 to prevent 95 any vacuum forming so that all of the water will be positively discharged through the pipe 13, whose discharge end is disposed below the disk 33. Therefore all water to the level of port 46 will siphon out. Water continues to flow into the tank 12' until it starts to raise the float 49. However, previous to the positive closing of the valve the float 49 rises sufficiently to permit the valve 23 to seat, and further upward movement 100 of the float causes the valve 43 to close port 46 and engage the seat 41. Water now flows through the passage 35 and thence through port 47 into the chamber 8. This operation continues until a sufficient air pressure has 105 been built up in the chamber 8 to force the disk 33 to engage the seat 32', and against the pressure of the incoming water supply. This is possible due to the difference in area 110 between the disk 33 and the seat 32'. The valve operates without noise due to the fact that the air pressure above the water in the chamber 8 acts as a cushion to prevent the objectionable noise in the pipes due to 115 the quick action of the disk 33. 120

It will be further noted that when the valve 39 is actuated to empty the tank 12', that not only the normal contents of the tank will be used to flush the closet bowl, but that a certain quantity of water from 125 the main supply will pass through the valve and aid in flushing the bowl.

What is claimed is:

1. A valve of the class described comprising a casing having a combined water and 130

air pressure chamber, a seat within the chamber, a valve held normally engaged with the seat by the combined pressure of the water and air within the chamber, means for discharging water from the chamber, and float operated means for admitting a fresh supply of air to the chamber during each discharging operation, as and for the purpose set forth.

10 2. A valve of the class described comprising a casing having a combined water and air pressure chamber, a valve within the chamber, means for discharging water from the chamber, and float operated means for admitting a fresh supply of air to the chamber during the discharging operation, said valve serving to control the ingress and egress of water from a main supply to and from the chamber.

20 3. A valve of the class described comprising a casing having a combined water and air pressure chamber, a water inlet pipe extending into the chamber and having a seat, an outlet pipe leading from the casing, a valve within the casing normally engaged with the seat, means for discharging the water from the chamber to release the pressure therein to permit the valve to unseat, whereby water from the inlet pipe flows to the outlet pipe, and float operated means for admitting a fresh supply of air to the chamber during the discharging operation.

4. A valve of the class described comprising a casing having a combined water and air pressure chamber, a water inlet pipe connected with the casing and having a seat on its upper end, an outlet pipe leading from the casing, a valve normally engaged with the seat, said valve having a passage therethrough to permit water to flow into the chamber to build up air pressure therein, said valve being held seated by the combined water and air pressure within the chamber, means for discharging the water from the chamber preceding the unseating of the valve, said valve controlling the passage of the water from the inlet pipe to the outlet pipe, and float operated means for admitting a fresh supply of air to the chamber during the discharging operation.

5. A valve of the class described comprising a casing having a combined water and air pressure chamber, an inlet pipe extended into the chamber, the upper end of said pipe constituting a seat, a flexible valve disk mounted in the casing and normally engaged with the seat, said valve having a water passage formed therein, a second valve operable in the chamber and normally disengaged from the first named valve, said second named valve having a seat carried thereby, means for actuating the second named valve to discharge the water from the chamber, the first named valve being adapted to engage the second named seat to prevent water from

passing through said passage to the chamber during the discharging operation, as and for the purpose set forth.

6. A valve of the class described comprising a casing having a combined water and air pressure chamber, a flexible disk valve mounted in the chamber, a water inlet pipe extended into the chamber and having a seat for normally engaging said valve, a second valve reciprocally mounted in the chamber and operable to discharge the water therefrom, and being normally disengaged from the first named valve, said valve having a seat associated therewith for engaging the first named valve previous to and during the discharging operation, there being an outlet pipe from the chamber for discharging water from the inlet pipe when the second named seat is engaged with the first named valve.

7. A valve of the class described comprising a casing having a combined water and air pressure chamber, a fixed valve seat located in the chamber, a movable valve seat also located in the chamber, a valve normally engaged with the fixed seat, means for discharging the water from the chamber, the movable seat being adapted to engage said valve previous to and during the discharging operation, and means for admitting a fresh supply of air to said chamber during each discharging action.

8. A valve of the class described comprising a casing, a float arm pivotally connected with the casing, said casing having a combined water and air pressure chamber, an air valve carried by the casing, a second valve operable in the chamber, said valves being operable by the float arm to respectively admit air to the chamber and to cause the water to discharge from the chamber.

9. A valve of the class described comprising a casing having a combined water and air pressure chamber, a float arm pivotally connected with the casing, a tubular guide depending into the chamber and having a casing on its lower end provided with ports, a stem mounted for vertical movement in the guide, a valve on the lower end of the stem and operable in the second named casing, a seat associated with the valve, a disk valve mounted in the chamber, an inlet pipe extended into the chamber, a seat on the upper end of the pipe for normally engaging the disk valve, an outlet pipe for the chamber, said disk valve having a water passage formed therein, said arm when moving downwardly serving to operate the first named valve through the medium of the stem to uncover one of said ports, thereby discharging the water therefrom, the first named seat when in its lowermost position being adapted to engage the disk valve to close the passage therein, whereby all water flowing from the inlet pipe will be com-

elled to flow to and from the outlet pipe, and an air valve associated with the casing and operable by the downward movement of the float arm to admit a fresh supply of air 5 to the chamber.

10. A valve of the class described, in combination with a tank, said valve comprising a casing having a combined water and air pressure chamber, a tubular guide depending into the chamber, said guide having a casing formed at its lower end and provided with ports, a stem for the guide, a valve on the lower end of the stem for operation in the second named casing, a seat associated 15 with said valve, an inlet pipe extended into the chamber and having a seat on its upper end, a disk valve mounted in the chamber and normally engaged with the second named seat, said disk valve having a water 20 passage formed therein, a float arm connected with the casing for moving the stem downwardly when the tank is discharging, whereby one of said ports is uncovered by the first named valve to cause water within 25 the chamber to pass through the guide into the tank, said disk valve being engaged with the first named seat to close said passage, whereby all water from the inlet pipe will be directed to the tank, and means operable 30 by the arm to admit a fresh supply of air

to the chamber, as and for the purpose set forth.

11. The combination with a tank having a water inlet pipe, of a valve comprising a casing having a water and air receiving chamber, the upper end of said inlet pipe being connected with the casing and extended into the chamber and constituting a valve seat, a valve normally engaged with the seat, a second valve located in the casing, 35 means for transferring water from one side of the first named valve to the other side, a float arm associated with the casing for actuating the second named valve for cutting off the flow of water through the transferring 40 means, means for conducting water from the inlet pipe to the tank, means for discharging water from the chamber, and means operable by the float arm for admitting fresh 45 air to the chamber to cause the water within the chamber to discharge therefrom to the tank, as and for the purpose set forth.

In testimony whereof we have hereunto set our hands in presence of two subscribing witnesses.

HJALMER C. GUSTAFSON.
